UNITED STATES PATENT OFFICE.

KAZIMIERZ ULRYCH, OF PHILADELPHIA, PENNSYLVANIA, ASSIGNOR OF ONE-HALF TO JOSEPH KULAK, OF PHILADELPHIA, PENNSYLVANIA.

DESIGN FOR A CLOTHES-WASHING IMPLEMENT.

47,548.

Specification for Design.

Patented July 6, 1915.

Application filed March 18, 1915. Serial No. 15,836. Term of patent 7 years.

To all whom it may concern:

Be it known that I, KAZIMIERZ ULRYCH, a subject of the Czar of Russia, residing at Philadelphia, in the county of Philadelphia and State of Pennsylvania, have invented a new, original, and ornamental Design for Clothes-Washing Implements, of which the following is a specification, reference being had to the accompanying drawing, forming part thereof.

The figure is a view in perspective of a clothes washing implement, showing my new design.

I claim:—

The ornamental design for a clothes washing implement, as shown.

KAZIMIERZ ULRYCH.
